Joseph O. Keller Inventor

UNITED STATES PATENT OFFICE.

JOSIAH O. KELLER, OF FORT WAYNE, INDIANA.

DESIGN FOR A DENTAL CABINET.

SPECIFICATION forming part of Design No. 21,666, dated June 28, 1892.

Application filed May 14, 1892. Serial No. 433,050. Term of patent 14 years.

To all whom it may concern:

Be it known that I, JOSIAH O. KELLER, a citizen of the United States, residing at Fort Wayne, in the county of Allen and State of Indiana, have invented and produced a new and original Design in Dental Cabinets, of which the following is a specification, reference being had to the accompanying drawing, forming part thereof.

10 The annexed drawing represents a view in perspective of my newly-designed dental cabinet.

15 The leading feature of my design consists of a base A, surmounted by a cabinet B of peculiar ornamental design.

The cabinet B consists of a rectangular portion O and the wings E and E' and is of a width equal to that of the base, but of considerably less depth. The central rectangular portion 20 O has an open part D below, but is provided with bevel mirror-panels M and M' on the front of the upper portion. The central por-

tion O is also surmounted by a pyramidal top G, highly ornamented. The wings E and E' have bevel-panels, through which the front 25 of the various ornamental drawers may be seen, affording a pleasing effect. The shelves F and F' are ornamented by the carved brackets I and I', forming artistic accessories. The filling-in portions P and P' are also ornamented by carved brackets and bevel-mirrors, only one of each appearing in the drawing—viz., H and K, respectively. These brackets and mirrors harmonize with brackets I and I' and mirrors M and M' and give a pleasing 30 35 contour to my cabinet.

What I claim is—

The design for a dental cabinet herein shown and described.

J. O. KELLER.
